UNITED STATES PATENT OFFICE

WILLIAM C. VIZARD, OF BROCKTON, MASSACHUSETTS, ASSIGNOR TO PERLEY E. BARBOUR, TRADING AS BARBOUR WELTING COMPANY, OF BROCKTON, MASSACHUSETTS

DESIGN FOR A LEASH OR ANALOGOUS ARTICLE

Application filed January 25, 1930. Serial No. 34,285. Term of patent 3½ years.

To all whom it may concern:

Be it known that I, WILLIAM C. VIZARD, a citizen of the United States, residing at Brockton, in the county of Plymouth and Commonwealth of Massachusetts, have invented a new, original, and ornamental Design for a Leash or Analogous Article, of which the following is a specification, reference being had to the accompanying drawing, forming a part thereof.

In the drawing, the figure is a view, in

perspective, of a leash showing my new design.

The dominant feature of my design consists of lateral stripes on each edge of the leash but not continued across the sides thereof.

I claim:

The ornamental design for a leash, or analogous article, substantially as shown and described.

WILLIAM C. VIZARD.
